KURT ELTZE, OF MANNHEIM-KAFERTAL, GERMANY, ASSIGNOR TO DAIMLER-BENZ AKTIENGESELLSCHAFT, OF STUTTGART-UNTERTURKHEIM, GERMANY, A COMPANY OF GERMANY

INTERNAL COMBUSTION ENGINE

Application filed January 12, 1928, Serial No. 246,829, and in Germany January 19, 1927.

This invention relates to improvements in and connected with internal combustion engines and more particularly to engines of the kind in which tappet mechanism is employed 5 for operating the valves.

The object of the invention is to provide a simplified construction and arrangement adapted for enabling the cam shaft, cam shaft bearings and housing, and the tappet 10 guides to be readily removed in a very convenient manner.

According to this invention, the cam shaft bearings, and the tappet guides associated therewith are removably mounted upon the 15 engine body either as a combined unit or as separate units. In carrying out the invention, it is advantageous to provide means displaceable axially of the cam shaft for the mounting or dismounting of the valve gear, 20 and it is of further advantage to adapt these means so that they are capable of adjustment, for the purpose of enabling the cam shaft to be adjusted with accuracy for attaining correctness of mesh of its driving gear.

25 In carrying out the invention, the cam shaft housing supports are provided by bearings for the cam shaft, which bearings are mounted in the end walls of the engine body; more particularly in the case of cylinder 30 block engines.

These improvements simplify the construction of a block of cylinders and facilitate the production thereof as well as the production and fitting of the cam shaft housing.

35 In order to enable the invention to be readily understood reference is made to the accompanying drawings illustrating one example of a practical construction embodying these improvements, in which drawings:—

40 Figure 1 is a side elevation of an engine with the removable valve gearing, parts of the cam shaft housing and bearings shown in section.

45 Figure 2 is an end elevation of Figure 1, but with parts of the engine body broken away and the cam shaft housing in section. Figure 2 also shows overhead parts of the valve gear which are omitted from Figure 1.

50 Figure 3 is a sectional end elevation of eccentric supporting means for the cam shaft.

In the example illustrated in the drawings, the engine comprises a cylinder block or monoblock which is indicated by the reference letter *a*. In one side of the cylinder block there is removably attached the cam shaft housing *b* and the latter supports guides for the tappets which operate the valves. The housing *b* is carried by the ends of bearing sleeves *c* and *d* which engage into the housing as supporting centres, as shown. 55 The sleeves *c* and *d* provide bearings for the cam shaft disposed within the housing and they are inserted into holes drilled or bored in the end walls of the cylinder block *a*, the said sleeves being formed with end flanges 60 or heads which come against the exterior of the said end walls when the sleeves are inserted from the exterior so that their inner ends engage into the ends of the housing *b* which is disposed within a cavity in the cylinder block. Further bearings for the cam shaft 65 are mounted inside the housing *b*, as shown in Figure 1 underneath the outermost left hand tappet.

70 As will be seen from the drawings, in the example illustrated, the housing *b* is formed with upwardly extending tubular guides for the upwardly extending tappets, these tubular guide parts being connected together by webs. The latter are formed with suitable 75 bosses, where required, and bolts *g* passed through these bosses into the engine block, as seen in Figure 2, serve for fixedly mounting the housing and tappet guides within the cavity above referred to. This cavity 80 may be closed by a cover plate *f*, also as seen in Figure 2.

85 The length of the housing *b* is such that, after endwise withdrawal of the bearing sleeves *c*, *d* from their holes in the cylinder block and the consequent disengagement of such sleeves from the housing, the latter can be removed from the engine block if desired, together with the cam shaft, the removal of the latter with the housing being possible 90 after removal of the gear wheel *e* from such shaft and by an endwise withdrawal in an inclined position of such shaft.

95 It is possible to arrange the bearing sleeves *c* and *d* so that there is an eccentricity of the 100

shaft axis in relation to the holes in which the sleeves are mounted, as shown in Figure 3. By rotatively adjusting the sleeves within the said holes it is possible to adjust to a 5 nicely the distance of the cam shaft axis from the crank shaft axis and thereby compensate for constructional inaccuracies which might otherwise adversely affect the meshing of the toothed gear *e* with another 10 gear on the crank shaft.

What I claim is:—

1. An internal combustion engine comprising tappet valve gear including a cam shaft, a housing enclosing the cam shaft, cam 15 shaft bearings inside the housing and tappet guides on the housing, the said housing, bearings, and tappet guides being removable from the engine as a unit, and endwise removable supports for the housing, the said 20 supports being capable of being moved axially in relation to the cam shaft to allow the valve gear to be mounted upon and removed from the engine.

2. An internal combustion engine with 25 tappet valve gear having a cam shaft, a cam shaft housing, cam shaft bearings and tappet guides associated with the housing, the said cam shaft bearings consisting of sleeves acting as supports for the cam shaft housing, 30 apertures in the end walls of the body of the engine to allow the said sleeves to be inserted endwise for engagement with the cam shaft housing, further cam shaft bearings inside the housing, the said cam shaft bearings inside 35 the housing and tappet guides being both mounted in a removable manner on the engine, as set forth.

3. An internal combustion engine comprising a crank casing, a cam shaft at a level 40 substantially below the top of the engine, cams and tappet gear for controlling the valves of the engine, a housing surrounding the cam shaft, cam shaft bearings inside the said housing, tappet guides carried by the 45 said housing, and means secured to the side walls of the crank casing for holding the said housing axially and enabling it to be removed as a whole, together with the cam shaft bearings and the tappet guides.

50 4. An internal combustion engine comprising a crank casing, a cam shaft at a level substantially below the top of the engine, cams and tappet gear for controlling the valves of the engine, a housing surrounding 55 the cam shaft, cam shaft bearings inside the said housing, tappet guides carried by the said housing, and endwise removable supports secured to the side walls of the crank casing, the said supports being capable of 60 being moved axially with respect to the cam shaft to allow the valve gear to be mounted upon or removed from the body of the engine.

In testimony whereof I have signed my name to this specification.
